UNITED STATES PATENT OFFICE.

PATRICK A. TOOMEY, OF CHICAGO, ILLINOIS.

TOILET-POWDER RECEPTACLE.

No. 824,391.

Specification of Letters Patent.

Patented June 26, 1906.

Application filed April 8, 1905. Serial No. 254,684.

To all whom it may concern:

Be it known that I, PATRICK A. TOOMEY, a citizen of the United States, and a resident of Chicago, in the county of Cook and State of Illinois, have invented certain new and useful Improvements in Toilet-Powder Receptacles; and I do hereby declare that the following is a full, clear, and exact description thereof, reference being had to the accompanying drawings, and to the letters of reference marked thereon, which form a part of this specification.

This invention relates to a novel toilet article designed as a convenient means of carrying and applying toilet powder.

The device, and especially that designed to be carried by the user, is so constructed as to permit the toilet powder to be readily applied when desired from time to time, while preventing accidental escape of the powder from the container or case. I have shown two general types of the device, one being designed more particularly to be carried by the person using the same, while the other is designed more particularly for use in the dressing-room.

The invention consists in the matters hereinafter set forth, and more particularly pointed out in the appended claims.

In the drawings, Figure 1 illustrates one embodiment of my invention and showing the manner of carrying it in a lady's pocket-book. Fig. 2 illustrates an axial section of the form of device shown in Fig. 1. Fig. 3 is a partial axial section of said embodiment of the invention, illustrating the manner of discharging powder therefrom. Fig. 4 is an enlarged detail section, showing the form of closure by which the powder is retained in the container or case and constructed to permit its ready discharge when desired. Fig. 5 illustrates an axial sectional view of another form of the device. Fig. 6 illustrates a form of the device designed more especially for use on the dressing-table.

The device shown in Figs. 1 to 4, inclusive, embraces a cylindric casing or tube A, which is closed at one end and is provided at its other end with a removable part A', that fits within the open end of the part A, either by telescopic or other suitable connection, and which when removed permits the tube A to be filled and when inserted into place closes the tube A. The removable part A' constitutes a continuation of the tubular receptacle

A. The outer end wall a' of said removable section A' is provided with an opening a, that is closed by a closure of such construction as to normally retain the powder therein, while allowing it to freely escape when the closure is moved off its seat. The seat and closure are so arranged as to have contact when the closure is in its closing position on a line or sharp angle as distinguished from a surface contact. The closure consists in the present instance of a conical plug B, which extends through the aperture a referred to. Said aperture a is made cylindric, and the conical plug engages the inner sharp angular margin of said opening, as more clearly shown in Fig. 4, whereby the line of contact of the plug with the angular margin of said aperture is a circular sharply-defined line of contact as distinguished from a surface contact. When the plug or closure is moved off its seat, therefore, there is afforded at once an annular passage around the plug through which the powder is allowed to escape freely. This construction also avoids liability of the powder being retarded in its escape through the passage thus formed between the conical closure and its seat in a manner to clog the said annular discharge-passage. Moreover, the sharp or angular margin of the aperture of the end wall a' of the casing avoids the packing or caking of the powder between the plug and its seat, as by reason of the cutting action of said angular seat any powder tending to remain on the tapered face of the closure will be removed by the cutting action of said angular seat. The plug or closure is held outwardly in its closing position by means of a suitable spring, herein shown as consisting of a spiral expansively-acting spring C, bearing at its inner end against a shoulder in the removable section A' of the casing and at its outer end against the plug. The plug is provided with a short inwardly-extending stud b, about which the spring fits to hold the parts in their proper relative positions. The shoulder herein shown, against which the inner end of the spring C bears, consists of an annular flange a² at the inner end of the removable section A'.

The stop or shoulder for the inner end of the spring may, however, be otherwise formed. In the construction shown the closure and its spring are self-contained within the extension A', which may be termed a "stopper" for the tubular receptacle A, so that the removal of said part A' for refilling

the receptacle does not in any manner affect the spring and closure. The outer face of the end wall a' , in which is formed the outlet-opening a of the receptacle, is depressed or 5 made concave, and the outer end of the closure B extends sufficiently beyond the concave face of the end wall to permit the closure to be pressed inwardly away from its seat, as by the tip of the finger or otherwise, 10 to allow escape of powder from the receptacle. Such depression in the end wall a' permits the plug to be forced inwardly sufficiently to amply open the valve, while avoiding an objectionable extension of the plug 15 beyond the wall, such as would be likely to fully open the valve by the accidental striking of external objects, and thereby inopportunistly spill powder from the receptacle.

The form of device shown in Figs. 1 to 4, 20 inclusive, is designed to be made small, so as to be conveniently carried by the user. For instance, it may be carried in a woman's pocket-book D , as shown in Fig. 1, it being confined between the side compartments of 25 the pocket-book inside the hinge thereof by means of a loop or loops d or otherwise. The device is also adapted for use by a man for applying a toilet-powder after shaving and is of such size and form as to be readily carried in the vest-pocket for this purpose. The 30 spring C is made of such strength as to effectively close the device to prevent accidental escape of powder therefrom, and the form of the closure and its seat described is such 35 as to instantly provide for an ample escape or discharge of the powder at the instant of the opening of said closure.

In Fig. 5 I have shown a device embodying the general principles of the device above referred to and designed for use on a dresser-table or to be carried in a woman's handbag. The device shown in Fig. 5 comprises a box E , provided with a removable cover E' , having therein an aperture through which the powder is adapted to escape or be discharged. 45 The aperture is normally closed by a closure e , which is spring-pressed to its closing position and is made and operates in the same general manner as the closure before described. In the present instance the closure is attached to the free end of a leaf-spring e' , the other end of which is attached to the under face of the removable cover E' of the box. This form of device is intended to be used 55 substantially like the form shown in the previously-described figures, it being reversed or turned upside down and the closure e pressed inwardly by contact with an external object to permit the powder to escape 60 therefrom.

In Fig. 6 is shown a device made somewhat similar to that shown in Fig. 5, but adapted to be used in a different manner. In the device shown in Fig. 6, F designates a box 65 provided with a removable cover F' . Said

cover F' is provided with a large central opening f for the escape of the powder, and this opening is normally closed by a plate-like closure f'' , that is provided with a conical or tapered marginal face f'' , engaging the angular margin of the opening f in the same manner which the conical or tapered closures of the construction previously described engages the angular margins of the apertures thereof. The closure f'' is held against its seat in the 75 last-illustrated construction by means of a spiral expansively-acting spring G , which is interposed between the inner face of the closure and bottom wall of the box. The lid or cover F' is depressed in the same manner 80 that the end wall a' of the device shown in Figs. 1 to 4 is depressed, and the outer face of the closure extends but little, if any, above the plane of the top of the receptacle.

In the use of this form of device it is designed that a powder-puff or the like shall be struck with some force against the upper face of the flat closure F . When so struck, the said closure yields inwardly against the action of the spring G , and the sudden inward 90 yielding of the closure acts to pneumatically force the powder from the box through the annular space between the closure and its seat, whereby the same is brought into contact with and clings to the powder-puff or 95 like articles and by which the powder is applied.

I claim as my invention—

1. A receptacle for toilet powder provided in its wall with a discharge-opening surrounded by a sharp seat located at the inner surface of said wall and a spring-pressed outwardly-tapered closure, the conical surface of which presses against said sharp seat to close said opening, and the smaller, outer end of which projects outside of the outer face of said wall. 100

2. A receptacle for toilet powder provided in its wall with a discharge-opening and a spring-pressed closure within the receptacle closing outwardly against said seat, said seat 110 and closure being formed to meet along a sharply-defined line, the wall containing said discharge-opening being depressed or concave on its outer face and said closure extending outwardly beyond the depressed 115 face of said wall.

3. The new article of manufacture comprising an elongated tubular toilet-powder receptacle closed at one end and provided at its other end with a removable tubular extension constituting a lid or cover and provided in its end wall with a discharge-opening, a closure for closing said opening and an expansively-acting closing-spring within said extension interposed between the closure and 120 an abutment carried by the extension and serving to hold the closure normally against its seat while permitting the closure to be yieldingly forced from its seat. 125

4. The new article of manufacture com- 130

prising an elongated tubular toilet-powder receptacle closed at one end and provided at its other end with a removable tubular extension constituting a lid or cover and provided in its end wall with a discharge-opening surrounded by a seat, an inwardly-opening closure within the extension engaging said seat, said seat and closure meeting along a sharply-defined line, an expansively-acting closing-spring within said extension and an interior shoulder carried by the extension between

which and the closure said spring is interposed.

In testimony that I claim the foregoing as my invention I affix my signature, in presence of two witnesses, this 5th day of April, A. D. 1905.

PATRICK A. TOOMEY.
